UNITED STATES PATENT OFFICE.

JAMES F. BAUMGARDNER, OF STONEBORO, PENNSYLVANIA.

AIR COOLER.

Application filed March 28, 1927. Serial No. 179,114.

This invention relates to an improved device which may be referred to as an air cooler, the same having more particular reference to a structure of this kind which is adapted to be disposed in the air circulating chamber of a refrigerator for subjecting the air to a tortuous passage, whereby it will be efficiently cooled.

Briefly, the invention has reference to a structure which is made up primarily of two main separable sections both of which are adapted to be filled with ice or other cooling medium to cool the surfaces against which the air is adapted to pass. The sections are readily separable and of a construction to permit them to be easily filled with ice and when they are assembled they form air passages in a body which may be readily supported in a roller carriage such as can be easily rolled into the air circulating compartment of the refrigerator box.

My principal aim is to generally improve upon structures of this class by providing one of comparative simplicity and durability, which is of such construction as to render it highly practical in operation and otherwise efficient in use.

Other features and advantages of the invention will become apparent from the following description and drawings.

In the accompanying drawings forming part of this application and in which like numerals are employed to designate like parts throughout the same:

Figure 1 is a longitudinal section thru an ice box showing the complete device arranged therein.

Fig. 2 is a perspective view of one embodiment of the device removed from the ice box.

Fig. 3 is a view like Fig. 2, showing a slightly different embodiment of the invention.

Fig. 4 is a small view in bottom plan of the structure shown in Fig. 3.

Fig. 5 is a perspective view of one of the half sections or part of the cooler.

Attention is first invited to Fig. 1, wherein it will be seen that the reference character 1 designates an elongated ice box including a compartment 2 in which the improved device is movably mounted. This ice box has a removable cover 3.

The principal part of the improved device comprises a box-like cooler which is composed of a pair of complementary half

sections 4 and 5 respectively. The section 4 comprises a hollow ice container which is inclined on one side and provided in this inclined side with a plurality of longitudinally spaced air conducting channels 6. This section is open at its top and a hinged cover 7 having an operating knob 8 is provided for said top.

As shown better in Figs. 2 and 3, this cover is provided in its swingable edge with notches which are located for alinement with the channels, so as not to obstruct circulation of the air. The complementary half section 5 is also in the form of an ice container and this is of somewhat triangular configuration in end elevation. The inclined side thereof rests against the correspondingly inclined side of the first-named section 4 as shown plainly in Fig. 1. This side is provided with arcuate or segmental extensions 9 of hollow configuration and these are located for reception in the air circulating channel 6.

Attention is directed to the fact that the channels are slightly deeper than the tongues 9, thus providing air circulating passages between the complementary surfaces of the tongues and the walls of the channels. This section of the box is also open at its top, and a hinged cover 10 of solid form is provided therefor. Obviously, when the two sections of the box are placed in superposed relation, they provide a two-part container, of rectangular outline in end elevation.

By considering Fig. 5 it will be noticed that the section 5 comprises a drain pipe 11 having a discharge 12 and connected by suitable branches with the arcuate tongues 9. Incidentally, in the several embodiments of the invention shown, the box structure is composed of the same two sections 4 and 5 of the construction already described. The only distinction is in the drain means.

For instance, in Fig. 5, the drain means comprises a pipe 11 and 12 just described, whereas in Fig. 2 it also comprises a pipe 13 connected with the front wall of the section 5 through the medium of branches 14. The pipe 13 is also provided with a discharge neck 15. In Fig. 3, these pipes are not provided, owing to the special configuration of the channels and tongues. In this arrangement, the channels and tongues are disposed on the under side of the box as represented in Fig. 4. However, they are des-

ignated by the same reference characters for they are substantially the same as already described. In the form of the structure shown in Figs. 3 and 4, I simply provide 5 two discharge necks 16 and 17 for the sections 4 and 5 respectively, these being located at one end of the structure as seen better in Fig. 4.

Of course, the construction of the means 10 for draining the containers depends a great deal on the location of the drain pipe 18 in the ice box.

In all of the embodiments of the invention I provide an outer casing or housing for 15 the superposed containers. For example in Fig. 1, I show an open top casing 19 having an opening 20 on its front side and at its bottom to accommodate the pipes 11 and 12. This constitutes a carriage and is provided 20 with rollers 21 so that it can be moved about freely in the ice box. If desired, a spacing block 22 may be interposed between the section 5 and the front wall of the casing. The same sort of a casing is provided in Fig. 2, except that supporting balls or legs 23 are 25 substituted for the rollers.

In the embodiment of the casing 24 shown in Figs. 3 and 4, the opening 25 instead of being in the front wall is located in the bottom for cooperation with the interfitting 30 tongues and channels.

In practice, the box-like sections are filled 35 with ice and are placed together so that the tongues extend into the channels. The walls of the tongues and channels become cooled by the ice and as the air passes against the surfaces, it naturally cools off and circulates about the compartment of the ice box.

It is believed that by carefully considering 40 the description in connection with the drawings, a clear understanding of the construction, the assembly of parts, the cooperation

of the details, and the advantages of the new organizations will be quite clear. Therefore, a more lengthy description is thought 45 unnecessary.

Minor changes coming within the field of invention claimed may be resorted to if desired.

Having thus described my invention, what 50 I claim as new is:—

1. In a structure of the class described, an air cooler comprising a box-like device composed of a pair of complemental sections, each section comprising a hollow ice container, one section being formed with channels, the other section being formed with tongues telescoping into and spaced from the walls of said channels, to provide curved 55 air circulating passages.

2. In a structure of the class described, an air cooler comprising a box-like device composed of a pair of complemental sections, each section comprising a hollow ice container, one section being formed with channels, the other section being formed with tongues, said tongues telescoping into and spaced from the walls of said channels, to provide air circulating passages, said sections being open at their tops, and individual 65 hingedly mounted members for said open tops.

3. In a structure of the class described, a box-like device composed of a pair of complemental containers having inclined surfaces disposed in meeting contact, said meeting surfaces being provided with co-acting channels and tongues, said tongues extending into said channels, said channels and tongues cooperating in interfitting spaced 70 75 relation to form air passages, and a casing for said device.

In testimony whereof I affix my signature.

JAMES F. BAUMGARDNER.
